UNITED STATES PATENT OFFICE.

CHARLES DUPUIS, OF VINCENNES, FRANCE.

METHOD OF MANUFACTURING KINEMATOGRAPHIC BANDS.

987,797.

Specification of Letters Patent. Patented Mar. 28, 1911.

No Drawing.

Application filed June 17, 1909. Serial No. 502,850.

To all whom it may concern:

Be it known that I, CHARLES DUPUIS, citizen of France, residing at 18 Rue de Paris, Vincennes, Seine, in the Republic of France, have invented new and useful Improvements 5 in Methods of Manufacturing Kinematographic Bands, of which the following is a specification.

Kinematographic bands are usually made 10 of a support of transparent celluloid covered with a silver bromid emulsion. Said bands are about 35 millimeters wide and 60 meters long or more. The images occupy 25 millimeters only on the above mentioned 15 width so that a margin is left on each side to receive feeding perforations which are made before the photographic operations.

My invention consists in a method for manufacturing kinematographic bands, which is 20 particularly intended for use when the images are printed by photomechanical means instead of a photographic process, said photomechanical means being particularly well adapted for printing a large number of 25 images, and also when the transparent support of celluloid is replaced by an opaque support, of metallized paper for instance, in view of lighting the images by reflection. My method may however be used for trans- 30 parent bands also, and for photographic printing but the best advantage thereof is obtained when printing by a photomechanical process on metallized paper.

My aim is first to save a large quantity of 35 the metallized paper heretofore used which I obtain by using a surface of metallized paper just equal to the total surface of the images themselves, without the margins for the perforations.

Another object of my invention is to re- 40 duce considerably the cost of manufacture of the blocks for photomechanical printing and also the cost of the printing operation. My method permits also of obtaining bands 45 of a considerable length deprived of any ob- jectionable increase of thickness and con- trolling the position of the perforations so as to cause the same to exactly correspond to the position of the images, in view of se- 50 curing absolutely stationary projections.

My invention will be hereinafter described 55 with reference to the manufacture of bands formed of brilliant metallized paper and in- tended to be lighted by reflection, the images being printed by any photomechanical proc-

ess such as phototypy, photo-engraving, heliotype, etc.

No machine exists for printing by such means in dimensions corresponding to the length of kinematographic bands, so that a 60 band of 80 meters for instance must be formed of 100 small bands of 80 centimeters joined end to end. If however the ends of 65 said small bands were superposed one upon the other in view of being glued together end to end, thickened parts would result 70 which would cause difficulties and breaking of the band to arise when unrolling the band through the passage of the projection machine, and thus materially affect the projection. This objection is removed, according 75 to my method by means of a support (a web of paper for instance) of a length corresponding to that of the band and bearing no impression. The images are printed 80 on thin metallized paper, the printed sheet of metallized paper is then cut into bands of a width equal to that of an image, and said bands are glued on the opaque supporting web in the middle of its width.

The series of images are printed side by side without leaving between them any space corresponding to the perforated margins of the kinematographic bands so that a considerable economy may be obtained in the man- 85 ufacture of printing blocks for photo-engraving, helio-engraving, photoglyphy, etc., the cost of which is calculated from the total printing surface. In the case of photog- 90 raphy a corresponding economy of sensitized paper is obtained. As kinematographic bands are 35 millimeters in width while images are only 25 millimeters in width, it may be seen that the economy obtained is very 95 considerable. For bands and images having special dimensions other than those above 100 stated it is obvious that a saving correspond- ing to the surface of the perforated margins may also be obtained.

My method is embodied as follows:

1. Printing plates or blocks are made by the known operations of the photomechanical process used, from the negative or the positive bands according to circumstances. Said plates or blocks reproduce the images of the band only and the whole surface thereof is formed of juxtaposed series of images, no space being left for the perforations. If, for instance, a phototypic process is applied, with a printing size of 55 by 81 110

centimeters, each plate comprises therefore a maximum of 22 bands of 81 centimeters long and 25 millimeters wide, the last number corresponding to the width of the images. On the contrary, if the band was printed with its lateral perforations, each printing plate of the same size would contain 15 bands of 81 centimeters long instead of 22.

10 2 By means of the printing plates or blocks obtained as above stated, the images are printed on thin metallized paper sheets.

3 After printing, the back of the sheets are covered with a layer of any glue such as 15 shellac.

4 The sheets are then cut into ribbons or tapes 25 millimeters wide, each of said tapes consisting of one series of images, any marking device having been used for securing a 20 proper registration when printing.

5 A paper roll of great length is then taken, said paper being sufficiently resisting for supporting the tensile strain applied by the feed drum on the perforations. Bands 25 35 millimeters wide are then cut from said paper web, and the printed bands 25 millimeters wide are glued thereon, at equal distance from the lateral edges and preferably at a hot temperature. The ends of the printed bands, when glued end to end on the web 30 may extend one upon the other for a length of a few millimeters or abut one against the other. In the first instance, the ends are superposed in such a way that there is no 35 risk of their being stripped off when sliding through the kinematographic apparatus. For this purpose the ends of the bands are glued so that the front end of each band is covered by the rear end of the preceding one 40 in the direction of the sliding movement. The small bands are of course glued according to the natural succession of the images. A kinematographic band is thereby obtained of any desired length, on a continuous support in one piece.

6 The kinematographic band obtained as above stated must be provided with feeding perforations, which operation is effected according to my method by the following 50 means which are one of the characteristic features of my invention.

Although the images of a band are supposed to be exactly equidistant on the whole length of said band, it is impractical to simply lead the same through a perforating machine of the kind usually used for kinematographic purposes, as the images would never correspond to the adjacent number of perforations, however exact the regulating of the 60 feeding mechanism may be. In said known machines, one perforation is made at each stroke on each side of the band so that any excess of a hundredth of a millimeter for instance in the stroke of the punching die 65 would cause an advance of a length ap-

proximately equal to that of one image between the series of perforations and the series of images on a feed of 9 meters assuming a picture 19 mm. in height and four picture holes per picture. Means must therefore be provided for permitting the intervening differences to be corrected as they are produced. To this end, I use a perforating machine by means of which four perforations corresponding to the height of an image may be simultaneously produced on each side of the band at each reciprocating stroke of the punching die. Said machine comprises a guiding or feeding comb having four teeth on each side, which are intended 70 to engage into the perforations. The distance between the comb and the dies corresponds to any number of images, *i. e.* four, eight or twelve perforations for instance, each image corresponding to four perforations. 75

The machine is provided with a slot or passage for the band, which passage has an opening receiving light from any suitable source and capable of being closed by any obturator while the band is fed by the mechanism. In front of the opening is located an objective so that the images may be projected on a screen as in a projecting machine. The machine is also provided with 90 two levers acting independently of each other while the machine is working, one for varying the stroke of the feeding comb and the other for varying the distance between the comb and the punching dies. 95

In operation, the operator observes the images projected on the screen and notices that said images ascend or descend slightly on the screen if the height of each image, *i. e.* the image pitch and the stroke of the feeding comb, *i. e.* the perforation feed do 100 not correspond exactly. The operator may then correct the perforation by means of the lever acting on the stroke of the feeding comb so that the image does not ascend nor descend farther on the screen, which shows that the image pitch and the perforation feed correspond temporarily. The operator may then act gradually by means of the second lever, on the distance between the 105 comb and the dies so as to center or frame the image again.

The perforating machine above described may obviously be also arranged for directly observing the images but in this case the result obtained in controlling the perforation of the band is less exact than in operating by projection. 110

In order to protect the printed images, the bands may be varnished, for instance 115 with a celluloid or an alcohol varnish.

Besides the above mentioned advantages it may be added that photomechanical printing is generally better and finer on thin paper than on thick paper and that the 120 130

printing plates are less strained thereby. Generally speaking, metallization is also easier and more brilliant on thin and resili-
ent paper. The images may however be
printed on a thick paper if desired, pro-
vided that a continuous support be used
and that the printed small bands be glued
thereon end to end without being super-
posed.

10 It may finally be remarked that by perfor-
ating the bands and projecting the images
at the same time, as above set forth, each
band becomes verified as far as the proper
order of the images, the faults, etc. are con-
cerned, said verification being necessary in
all cases.

In the event of the images being printed
by photography, sensitized layers, which re-
quire a very long insolation may then be
used, in spite of the comparatively long
time of exposition required, as a thousand
images for instance are printed at the same
time while by the known methods the images
must be printed successively.

25 Having now described my invention, what
I claim as new and desire to secure by Let-
ters Patent is:

1. A method of manufacturing kinemato-
graphic bands to be fed by means of lateral
30 perforations consisting in obtaining a re-
producing surface entirely covered by kine-
matographic images, no lateral margins be-
ing left for perforations on the sides of said
images, obtaining prints from said surface,
35 cutting said prints into bands, fixing said
bands on a resisting and continuous sup-
porting web of a sufficient width to receive

feed perforations and perforating said web,
substantially as described and for the pur-
pose set forth.

2. A method of manufacturing kinemato-
graphic bands consisting in obtaining an
unperforated web having kinemographic
images thereon, perforating said web while
projecting the images on a screen and assur-
ing the proper relative positions between
the succeeding images and perforations by
observing the succeeding positions of the
projected images on the screen, substan-
tially as described and for the purpose set 50
forth.

3. A method of manufacturing kinemato-
graphic bands consisting in obtaining an
unperforated web having kinemographic
images thereon, making perforations in the 55
web on a length corresponding to one image
at the same time, feeding the web inter-
mittently for a length corresponding with
the distance between the transverse axes of
two consecutive images, projecting the im-
ages on a screen and preventing any dis-
placement of the projected images on the
screen by controlling the distance between
the feeding and perforating means, sub-
stantially as described and for the purpose 60
set forth.

In testimony whereof I have signed my
name to this specification in the presence of
two subscribing witnesses.

CHARLES DUPUIS.
